[57] CLAIM

The ornamental design for a facsimile machine, as shown and described.

DESCRIPTION

FIG. 1 is a top, front and right side perspective view of a facsimile machine according to our design;

FIG. 2 is a rear, bottom and left side perspective view with kick-up stand maintaining the facsimile machine in an inclined, upstanding position;

FIG. 3 is a top plan view thereof;

FIG. 4 is a front elevational view thereof;

FIG. 5 is a right side elevational view thereof;

FIG. 6 is a rear elevational view thereof;

FIG. 7 is a left side elevational view thereof;

FIG. 8 is a bottom plan view thereof; and,

FIG. 9 is a left side elevational view thereof with the kick-up stand in a closed position.

1 Claim, 8 Drawing Sheets
